US00D710596S

(12) **United States Design Patent**
Morgan et al.

(10) **Patent No.:** US D710,596 S
(45) **Date of Patent:** ** Aug. 12, 2014

(54) **ARMBAND**

(71) Applicants: **Mark Edward Morgan**, Doral, FL (US); **Jytte Lilli Nielsen**, Doral, FL (US)

(72) Inventors: **Mark Edward Morgan**, Doral, FL (US); **Jytte Lilli Nielsen**, Doral, FL (US)

(**) Term: **14 Years**

(21) Appl. No.: **29/467,633**

(22) Filed: **Sep. 20, 2013**

Related U.S. Application Data

(63) Continuation-in-part of application No. 13/245,454, filed on Sep. 26, 2011, which is a continuation-in-part of application No. 11/509,122, filed on Aug. 24, 2006, now abandoned.
